UNITED STATES PATENT OFFICE.

GEORGE D. POGUE, OF ST. LOUIS, MISSOURI.

FUEL-PUMP FOR OIL-ENGINES.

1,254,846.

Specification of Letters Patent. Patented Jan. 29, 1918.

Original application filed July 18, 1915, Serial No. 40,678. Divided and this application filed February 11, 1916. Serial No. 77,628.

To all whom it may concern:

Be it known that I, GEORGE D. POGUE, a citizen of the United States, residing at St. Louis, Missouri, have invented a certain new and useful Improvement in Fuel-Pumps for Oil-Engines, of which the following is a full, clear, and exact description, such as will enable others skilled in the art to which it appertains to make and use the same.

10. This invention relates to variable feed fuel pumps for oil engines, the present application being a division of my co-pending application Serial No. 40,678, filed July 19, 1915, for improvements in variable feed 15 pumps.

The object of my present invention is to provide a variable feed fuel pump that is particularly adapted for use with internal combustion engines of the type that are 20 started with some other medium than liquid fuel, said pump comprising means for causing the starting medium to be cut off or rendered inoperative and for causing the liquid fuel to be supplied to the engine after the 25 engine has attained speed.

Figure 1 of the drawings is a vertical transverse sectional view of a multi-cylinder pump, constructed in accordance with my invention.

30. Fig. 2 is an enlarged rear elevational view of a portion of said pump.

Fig. 3 is an enlarged vertical sectional view, taken on the line 3—3 of Fig. 1.

Fig. 4 is a detail view of a mechanism 35 employed for adjusting the cam shaft and for holding said shaft in adjusted position; and

Fig. 5 is a perspective view of a cam shaft that co-operates with the actuating levers for 40 the tripping blocks.

I have herein illustrated my invention embodied in a multi-cylinder variable feed pump which is so designed that the connecting device of each plunger-operating mechanism is tripped automatically sooner or later on the suction stroke of the plunger, so as to vary the degree of movement imparted to the plunger on its displacement stroke, and thus regulate the supply from 50 the cylinder, but I wish it to be understood that my invention is not limited to a multi-cylinder pump or to a pump in which the connecting device of the plunger-operating mechanism is tripped or rendered inoperative 55 on the suction stroke of the plunger, as

my invention is applicable to a pump of the general type referred to, in which the connecting device of the plunger-operating mechanism is tripped or rendered inoperative sooner or later on the discharge stroke 60 of the plunger. Furthermore, while I have herein illustrated only one type of connecting device or connecting element for establishing connection between the fixed-stroke member and the variable-stroke member of 65 the plunger-operating mechanism, and have illustrated only one form of tripping device for rendering said tripping element inoperative, I wish it to be understood that it is immaterial, so far as my broad idea is concerned, what particular kind of connecting 70 element and tripping device are employed, so long as said co-operating parts are so designed and arranged that the variable-stroke member of the plunger-operating 75 mechanism will be automatically disconnected from the fixed-stroke member at such a period in the cycle of operations of the pump that the supply from the pump will vary.

80. Referring to the drawings, which illustrate the preferred form of my invention, A designates the plungers of a multi-cylinder pump, each of which reciprocates in a cylinder B provided with an inlet valve and one or more discharge valves. A separate and distinct operating mechanism is provided for each of the plungers A and all of said plunger-operating mechanisms are propelled or actuated from a single crank shaft C that is driven by some suitable means, (not shown), said shaft C having a plurality of cranks, each of which is connected by means of a connecting link 3 with one of the plunger-operating mechanisms, the cranks 85 on the shaft C either being set at the same angle, as herein shown, so that all of the cylinders will operate simultaneously, or set at different angles so that the cylinders will operate progressively, or one after the other. While I have stated that the plunger-operating mechanisms are operated by the crank shaft, it will, of course, be understood that it is immaterial what particular means is employed for actuating the plunger-operating 90 mechanisms. Each plunger-operating mechanism consists of a fixed-stroke member or primary actuating member D, a variable-stroke member E and a connecting device F that is interposed between the members D 95

and E so as to impart movement to the variable-stroke member E when the fixed-stroke member D moves in one direction. In the pump herein shown the connecting device F is so arranged that it will move the variable-stroke member when the fixed-stroke member is moving on its suction stroke. On the displacement stroke of the plunger the variable-stroke member E is moved positively by the fixed-stroke member D. The member D, which constitutes the primary actuating member of the plunger-operating mechanism, is preferably cylindrical-shaped, and the upper end of same is bifurcated so as to receive the link 3, said parts being pivotally connected together by a pin 3^a. The lower end of the member D is also bifurcated or slotted so as to form a housing for the connecting device F which is pivotally connected thereto by a removable pin 4. The two side parts of the bifurcated portion of the lower end of the member D are connected together by an element 5 so as to produce a strong and rigid structure, the connecting element herein illustrated consisting of a ring 5 screwed onto the lower end of the member D and provided at its upper end with a vertically-disposed flange that fits in an annular groove in the lower end of the member D. The variable-stroke member E is arranged in longitudinal alinement with the member D and is provided at its upper end with a hook-shaped portion 7 that projects upwardly into the slot in the lower end of the member D, so that the hook or projection 7 thereon will coöperate with the hook or projection 8 on the connecting device F, as shown in Fig. 1. The variable-stroke member E is provided with a cylindrical shank 9 that fits in a guideway formed in a transverse member 10 of the frame of the pump, and the primary actuating member D also fits in a guideway formed in a transverse member 11 of the frame of the pump that is arranged above the member 10. The plunger A is securely connected to the lower end of the variable-stroke member E in some suitable manner, so that it will be moved positively upwardly and downwardly by the member E.

On the displacement stroke of the primary actuating member D the ring 5 at the lower end of said member bears upon a head 9^a on the variable-stroke member E, and thus positively moves the plunger A downwardly. On the return stroke or upward stroke of the primary actuating member D the connecting device F thereon, which is normally held in engagement with the hook-shaped portion at the upper end of the variable-stroke member E by means of a spring 4^a, causes the member E to move upwardly until the connecting device F is tripped by a means that will be hereinafter described.

The space between the transverse members 10 and 11 is closed at the front by a removable cover plate 19, as shown in Fig. 1, and at the rear of said space is a cover plate 20 which carries certain elements of the tripping mechanism with which the connecting devices F coöperate.

The mechanism for governing the supply from the pump consists of a plurality of tripping devices that trip the connecting devices F or cause said connecting devices to be rendered inoperative sooner or later on the suction stroke of the plunger-operating mechanisms. A tripping device is provided for the plunger-operating mechanism of each cylinder, and all of said tripping devices are under the control of an automatic governing device. When my improved pump is used in connection with an internal combustion engine for feeding fuel to the cylinders of the engine, the means that controls said tripping devices will be operatively connected with the governor of the engine, so as to cause the connecting devices F of the respective cylinders to be tripped sooner or later on the suction strokes of the plungers, according to the speed of the engine, thus causing varying quantities of fuel oil to be drawn into the cylinders of the pump and thereafter fed to the cylinders of the engine on the displacement stroke of the plungers. In order that the plunger-operating mechanism of one cylinder may be rendered inoperative, so as to cut one cylinder of the pump out of service, without affecting the other cylinders, I have constructed the actuating mechanism for the tripping device in such a manner that the operator in charge of the pump can cause the connecting device of one plunger-operating mechanism to be held in an inoperative position without disturbing or affecting the operation of the other plunger-operating mechanisms. I have also constructed said mechanism in such a manner that all of the tripping devices can be moved simultaneously into such a position that all of the plunger-operating mechanisms are maintained in an inoperative condition. In various types of internal combustion engines with which my improved pump can be used successfully it is customary to start the engine by means of compressed air, an electric motor or some other suitable source of power, and then throw the fuel supply pump into operation, so as to feed fuel to the cylinders after the engine has reached normal speed. In order that this may be effected easily I have provided my pump with a controlling means that governs the medium used to start the engine and also governs the pump, said means being so constructed that the pump will come into operation automatically and supply liquid fuel to the cylinders of the engine after the starting means has

been cut off or rendered inoperative. The tripping devices of the pump herein shown consist of sliding blocks G that coöperate with friction rolls 30 on rearwardly-projecting arms on the connecting devices F in such a manner that each of said devices F will be disengaged from its coöperating variable-stroke member before the primary actuating member D that carries said device 10 reaches its upper limit of movement. The blocks G are slidingly mounted in slots or guideways in the plate 20 and are retained in operative position in said plate by means of keepers or cover plates. Each of said 15 blocks has a flat surface *x* that lies parallel to the axis of the main moving parts and also an inclined or oblique surface *y*, as shown in Fig. 1, the position of said surfaces being such that the friction roll 30 of each 20 connecting device F will travel over the inclined surface *y* of its coöperating tripping block and then onto the surface *x* on said block during the upward stroke of the primary actuating member D, the movement 25 that is imparted to the connecting device F, by reason of the roll 30 thereon coming into engagement with the tripping block G, causing said connecting device F to be automatically disengaged from the variable-stroke 30 member with which it coöperates. Each of the tripping blocks G is provided with an actuating lever H which is connected to same by means of a ball-shaped, or substantially ball-shaped, head 31 on the lever that projects into a cylindrical hole in the rear side 35 of the block. The levers H are mounted on a rock shaft 32 which extends transversely of the pump and which is mounted in bearings 33 on the plate 20 or some other suitable part of the frame. When the pump is 40 used in connection with an internal combustion engine for feeding fuel oil to the cylinders of the engine, the rock shaft 32 will be operatively connected with the automatic governor of the engine in such a manner 45 that the position of said rock shaft will change when the collar 1 of the governor moves up and down, owing to variation in the speed of the engine, the means herein 50 illustrated for transmitting movement from the governor collar 1 to the rock shaft 32 consisting of an arm 32^a on the rock shaft 32, and a link 34 that joins said arm to a lever 55 35 on a rock shaft which is provided with a rock arm 36 that is connected to the governor collar 1, as shown in Fig. 1. The actuating levers H are loosely mounted on the rock shaft 32, and adjustable means are provided 60 for determining the position of said levers with relation to said shaft, said means preferably consisting of adjusting screws 37 mounted in lugs formed on rigid collars 38 on said shaft and coöperating with stops or shoulders 39 on said actuating levers H. 65 Each of the tripping blocks G is under the

influence of a spring 40 which tends to move said block upwardly, and thus cause the projection 39 on its coöperating actuating lever to bear against the adjusting screw 37, as shown in Fig. 1. By adjusting the screw 37 70 the position of the tripping block that coöperates with said screw can be changed relatively to the governor-controlled shaft 32 that operates the lever H. In a multi-cylinder pump the relative amount of fuel 75 supplied by any cylinder may be increased or decreased by changing the position of the adjusting screw 37 that coöperates with said cylinder. Various other means could, of course, be employed for changing the positions of the actuating levers H with relation to the governor-controlled rock shaft 32 that imparts movement to said levers. Therefore, I do not wish it to be understood that my invention is limited to the particular 80 means herein illustrated. Furthermore, it is immaterial what particular form of mechanism is employed for actuating the tripping blocks, but I prefer to use a mechanism of substantially the construction shown, because it comprises comparatively few parts that can be easily assembled and adjusted, which parts are of such a design that lost motion is reduced to a minimum.

A cam shaft J that extends transversely 95 across the frame of the pump in proximity to the rock shaft 32 is provided with a plurality of cams 41 that coöperate with the actuating levers H and move them downwardly into such a position that all of the 100 connecting devices will be held out of engagement with the variable-stroke members E with which they coöperate, each actuating lever H being preferably provided with a friction roll 42 that is arranged in such a 105 position that it will be engaged by its coöperating cam 41 when the cam shaft J is turned into a certain position. In addition to the means just described for holding the connecting devices F in an inoperative position, I have provided each of the tripping blocks H with a hook 43 that is adapted to be engaged by a plunger 44, shown in Fig. 1, when the tripping block is moved downwardly below its normal position, by pulling 110 on the handle 45 of the lever H that actuates said tripping block.

If it is desired to cut one of the cylinders of the pump out of commission without affecting the remaining cylinders, the operator in charge of the pump grasps the handle 45 of the actuating lever H that coöperates with the tripping block of the cylinder that it is desired to render inoperative and pulls said handle rearwardly far enough to cause 115 the hook 43 at the lower end of the tripping block to be engaged by the spring-pressed plunger 44. Thereafter, the variable-stroke member of the plunger-operating mechanism with which said block coöperates will re- 120 125 130

main at rest while the other plungers of the pump continue in operation.

The cam shaft J is also utilized to govern a medium that is employed to start the engine with which the pump is used. During the interval it is required to bring the engine from rest up to approximately normal speed it is desirable to stop the delivery of fuel to the cylinders of the pump, otherwise abnormal pressures might be developed within the cylinders, which would subject the frame, shaft and related parts to dangerous stresses. After the engine has been brought up to approximately normal speed it is, of course, desirable to cut off or render inoperative the medium that started the engine and throw the pump into service in the shortest possible time, so as to not lose the momentum stored up in the fly wheel of the engine between the time when the starting medium is discontinued and the introduction of fuel into the cylinder begins. It is, of course, also desirable to have these two separate connections so interlocked that they cannot possibly occur at the same time. My improved pump is so designed that it accomplishes the desirable features above mentioned, for, as previously stated, the cam shaft J that renders the tripping blocks inoperative is also utilized to govern the medium which starts the engine. In case compressed air is used as the medium to start the engine, a valve 50 that governs the supply of compressed air is combined with a valve-operating device 51 that is under the control of a cam 52 on the cam shaft J. When said cam shaft J is in such a position that the cams 41 thereon hold the tripping blocks G depressed or in such a position that the connecting devices F of the plunger-operating mechanisms are rendered inoperative, the cam 52 on said cam shaft J will permit the valve 50 or other device that controls the starting medium to remain open or in an operative condition. While the engine is building up speed, or while it is being driven by the starting medium, the primary actuating members D of the plunger-operating mechanisms reciprocate back and forth, if the crank shaft C is connected with the engine, but the plungers in the pump cylinders remain at rest. Consequently, no fuel is drawn into the pump cylinders. After the engine has reached approximately normal speed, the cam shaft J is turned in such a direction that the cam 52 thereon will close the valve 50, and thus cut off the starting medium, the continued movement of the cam shaft in this direction causing the cams 41 thereon to be moved out of engagement with the actuating levers H, so that said levers and their cooperating tripping blocks can move upwardly far enough to release the connecting devices F, and thus cause said devices to impart movement to the variable-stroke members E of the plunger-operating mechanisms. If desired, the cams 41 can be so designed that the connecting devices F will be released progressively. The cam shaft J is provided at one end with a handle 53 for turning said shaft, and means are provided for locking said cam shaft in adjusted position, one means that may be used for this purpose consisting of a spring-actuated locking device 54, shown in Fig. 4, that cooperates with a notched disk 55 on the cam shaft. If desired, the handle 53 can be provided with a pointer 56 that travels over a dial 57 provided with the words "Stop," "Starting" and "Running," or other suitable indicia, so as to assist the operator in adjusting the cam shaft J. When the pointer 56 stands at the word "Stop" the cams 41 on the cam shaft J will hold the actuating levers H in their depressed position, and thus maintain the connecting devices F in an inoperative condition. When the cam shaft J is in this position the plungers of the pump remain at rest, even though the primary actuating members of the plunger-operating mechanisms are set in motion. When the cam shaft J is turned into such a position that the pointer 56 stands opposite the word "Starting" on the dial, the cam 52 on said shaft permits the valve 50 to open, and thus causes the engine to be started by the medium which said valve controls, the cams 41 being so arranged that they still hold the actuating levers H in their depressed position, and thus prevent the variable-stroke members of the plunger-operating mechanisms from moving when the primary actuating members D are set in motion by the starting of the engine. After the engine has reached approximately normal speed, the cam shaft J is turned in such a direction that the pointer 56 travels toward the word "Running" on the dial 57. During the first part of this movement of said shaft the cam 52 thereon closes the valve 50, and thus cuts off the starting medium, and during the latter part of the movement of the cam shaft the cams 41 thereon release the actuating levers H, and thus permit the connecting devices F to become operative for connecting the primary actuating members and the variable-stroke members of the plunger-operating mechanisms together. If desired, the cam shaft J can be provided with a ratchet wheel 58 that cooperates with a pawl 59, so as to prevent said cam shaft from being turned in the wrong direction, or, in other words, prevent the several functions just mentioned from being performed in an improper sequence after the engine has been started by the starting medium. In some instances it may be desirable to arrange the

cams 41 on the cam shaft J in such a manner that one or more of the pump plungers will remain in action while the engine is being started by an external starting force. It is, of course, immaterial, so far as my broad idea is concerned, what particular medium is used to start the engine, and while I have herein illustrated an air line and a controlling valve for starting the engine, it will be obvious that various other means could be used for this purpose comprising a controlling device whose position is determined by the cam shaft J or by the means that effects the manual adjustment of the tripping blocks.

Having thus described my invention, what I claim, and desire to secure by Letters Patent, is:

1. A fuel pump for supplying liquid fuel to an internal combustion engine provided with a plunger-operating mechanism that comprises a primary actuating member that moves when the engine is in operation, a variable-stroke member that imparts movement to the plunger of the pump and a connecting device for transmitting movement from one of said members to the other, a tripping device for rendering said connecting device inoperative sooner or later on one stroke of said plunger-operating mechanism, a mechanism combined with the governor of the engine for controlling said tripping device, a manually-operated means for holding said connecting device in an inoperative condition so as to cause the variable-stroke member to remain at rest when the primary actuating member is in operation, and a device under the control of said manually-operated means for governing a medium that is used to start the engine, said manually-operated means being so constructed that when it is moved to cause said controlling device to cut off the starting medium the connecting device of the plunger-operating mechanism will be rendered operative and thus cause the pump to feed fuel to the engine.
2. A fuel pump for supplying liquid fuel to an internal combustion engine provided with a plunger-operating mechanism that comprises a primary actuating member that moves when the engine is in operation, a variable-stroke member that imparts movement to the plunger of the pump and a connecting device for transmitting movement from one of said members to the other, a tripping device for rendering said connecting device inoperative sooner or later on one stroke of said plunger-operating mechanism, a mechanism combined with the governor of the engine for controlling said tripping device, a manually-operated means for holding said connecting device in an inoperative condition so as to cause the variable-stroke member to remain at rest when the primary actuating member is in operation, and a device under the control of said manually-operated means for governing a medium that is used to start the engine, 40 45 50 55 60 65

In testimony whereof I hereunto affix my signature in the presence of two witnesses, this seventh day of February 1916.
